UNITED STATES PATENT OFFICE

163,084

SOAP DISH OR THE LIKE

Herman Biener, Brooklyn, N. Y.

Application February 23, 1949, Serial No. 1,031

Term of patent 14 years

(Cl. D4—3)

To all whom it may concern:

Be it known that I, Herman Biener, a citizen of the United States of America, and a resident of Brooklyn, county of Kings, and State of New York, have invented a new, original, and ornamental Design for a Soap Dish or the like, of which the following is a specification, reference being had to the accompanying drawing, forming part thereof, in which:

Fig. 1 is a perspective view of a soap dish, showing my new design;

Fig. 2 is a face view thereof; and,

Fig. 3 is a cross sectional view taken on the lines 3—3 of Fig. 2.

I claim:

The ornamental design for a soap dish or the like, as shown.

HERMAN BIENER.
